UNITED STATES PATENT OFFICE.

CLARENCE H. ESTES, OF CHICAGO HEIGHTS, ILLINOIS, ASSIGNOR TO AMERICAN MANGANESE STEEL COMPANY, OF CHICAGO, ILLINOIS, A CORPORATION OF MAINE.

BAR FOR FOUNDRY FLASKS.

Application filed May 18, 1925. Serial No. 30,968.

This invention relates to bars which are arranged transversely between and supported upon opposite walls of a foundry flask for the purpose of subdividing the flask into 5 compartments, and providing means to prevent the body of sand which constitutes the mold from dropping out of the flask. Heretofore it has been the practice to place bars in bridging relation to the opposite sides of 10 a molding flask and to suspend from these bars so-called gagers which slip down to nearly the lower plane of the flask and support the sand against falling out. But this method is objectionable in that it often prevents 15 satisfactory ramming of the mold and adds to the difficulty of shaking out the sand of the mold.

The present invention has for its object 20 to provide a flask bar which may be used in any desired number, and which, while very effective in preventing the sand from falling through, will improve the ramming character of the mold and facilitate shaking out the sand when the mold is inverted.

The present invention proceeds upon the principle of providing a bar in the form of 25 a partition or subdividing wall having a length which adapts it to fit between opposite walls of a flask, and equipped for supporting it in the flask; said bar having formed upon its lower marginal portion lugs downwardly increasing in width and with upwardly enlarging spaces between them, said lugs being inwardly inclined from the 30 vertical plane of the bar and designed to present to the vertical load of the sand a plurality of inclined faces between which the sand will wedge and pack and which will prevent the body of sand, after it has been packed, from falling through the flask, also 35 spaces between the lugs through which the masses of sand in the compartments can meet and become united. The bars are cheaply and effectively produced with characteristics 40 described, by forming their lower margins with spaced dove-tailed lugs inclined alternately in opposite directions. Preferably, one face of the bar will be provided with 45 one or more horizontal ribs which stiffen the bar and serve as a further resistance to slipping of the body of sand; and preferably also the means for mounting the bar in the flask consists of a pair of end flanges slotted 50 in the longitudinal direction of the supporting sides and receiving attaching bolts,

mounted in the latter, in a manner to render the bars adjustable with respect to distances between the bars or between a bar and an end wall of the flask.

In order that the invention may be fully 60 understood, the preferred embodiment is shown in the accompanying drawing, in which—

Figure 1 is a bottom plan view of a molder's flask equipped with flask bars 65 constructed and mounted in the flask in accordance with the present invention.

Figure 2 is a vertical section taken longitudinally of the flask and transversely of the flask bars in a plane indicated by the 70 line 2^x—2^x of Figure 1.

Figure 3 is a vertical transverse section on the line 3^x—3^x of Figure 2.

A represents a molder's flask of known construction, and B represents flask bars 75 mounted in bridging relation between the side walls of the flask A and in a relation to subdivide the latter into a plurality of mold forming spaces. Each bar B consists of a vertical plate-like body portion 1, preferably formed on one face with sand sustaining ribs 2, end flanges 3 having slots 4 that receive bolts 5 as the means for securing the bars in the flask, and sand sustaining lugs 6 spaced at suitable intervals 80 along the bottom margins of the bars B and deflected alternately in opposite directions into the sand-receiving spaces of the flask, and thus providing along the opposite confines 85 of each flask subdivision, inclined faces 7 90 which receive the vertical load of the compacted body of sand and resist displacement of the latter, by wedging action that both renders the lugs effective in their sustaining function, and facilitates release of the body 95 of sand when the flask is inverted, particularly if the securing bolts 5 of one bar be loosened and the bar is slightly backed away from the sand.

I claim:

1. A bar for molders' flasks, consisting of a supporting member and lugs located at spaced intervals along the bottom margin of said member and inclined inwardly into the mold-forming space defined by the bar; said lugs enlarging downwardly.

2. A bar for molders' flasks, comprising a supporting member constructed along its bottom margin with spaced lugs inclined to the plane of the bar; said lugs enlarging

downwardly and the spaces between them enlarging upwardly.

3. A bar for molders' flasks, consisting of a supporting member having end flanges slotted to receive sustaining bolts, and having along its lower margin, at spaced intervals, inwardly inclined downwardly enlarging lugs.

4. A bar for molders' flasks, consisting of a vertical plate-like supporting member and lugs of dove-tail form located at spaced intervals upon the lower margin of said member and inclined inwardly into the mold-forming space defined by the bar.

5. A bar for molders' flasks, comprising a vertical plate having supporting flanges at its ends in positions to abut against opposite walls of a flask; said flanges being provided with substantially horizontal slots adapted to receive bolts for supporting the bars in the flask; and said plate being constructed upon its lower margin with lugs of dove-tail form extending inwardly into the forming space defined by the plate.

Signed at Chicago Heights, Illinois, this 25 day of April, 1925.

CLARENCE H. ESTES.
